FASTENER INSERTING MACHINE

Malcolm G. Bliss, Grafton, Mass., assignor to
United Shoe Machinery Corporation, Paterson,
N. J., a corporation of New Jersey

Application January 15, 1934, Serial No. 706,617

20 Claims. (Cl. 218—15)

This invention relates to fastener-inserting machines and is illustrated herein as embodied in a machine for inserting eyelets successively in a series. The invention is concerned chiefly with the problem of locating fasteners in a work-piece to produce an arrangement which is commonly referred to as "spread" in the art of eyeletting shoe-uppers. The so-called spread in this art consists in locating some or all of the eyelets of a series in a line that converges toward or diverges from the edge over which the lacing is to lie. The effect of spread is usually obtained by setting back the eyelets adjacent to the throat of an upper at a greater distance from the edge than those nearer the top of the upper.

The invention is herein illustrated as embodied in a high-speed power-operated machine of the type in which eyelets are inserted one at a time and in which the work is fed by automatic mechanism to space the eyelets one from another. A typical example of a machine of this type is illustrated and described in United States Letters Patent No. 1,228,768, granted June 5, 1917 on application of P. R. Glass. In a machine of this type the quarters of a shoe-upper are presented for operation one at a time and are fed along a work-supporting table under the guidance of an edge-guide. Moreover, in the use of such a machine the eyeletting progresses from the throat of one quarter toward the top but from the top of the other quarter toward the throat. Consequently, to obtain spread under such conditions, it is necessary to shift one of the quarters in one direction transverse to its normal path of feed at one or more intermediate points in a series and to shift the other quarter in the opposite direction at one or more intermediate points. Furthermore, to obtain symmetry of the two series the relative reversal of the two quarters requires the transverse shifting of one quarter to be timed differently from the corresponding timing pertaining to the other quarter.

The problem is further complicated by the fact that in machines of this type the work is normally clamped upon the supporting table by a presser-foot which is automatically retracted in each cycle only during the work-feeding period. It will therefore be appreciated that to provide for shifting a quarter transversely of its normal path of feeding motion requires specially timed retraction of the presser-foot to release the work.

With these conditions in view, an object of the present invention is to provide, in an automatic fastener-inserting machine of the work-feeding

type, improved means by which an article of work such as a shoe-upper may be guided and controlled in such a manner as to obtain spread and symmetry in the arrangement of the fasteners.

To this end, and in accordance with a feature of the invention, the machine herein illustrated is provided with an improved combination comprising a work-support, a presser-foot, manually operable means arranged to retract the presser-foot, power-operated mechanisms arranged to insert fasteners successively in a series and to feed the work to space the fasteners one from another, a clutch controlled by said manually operable means to operate said mechanisms, a movable edge-guide, a spring arranged to move the edge-guide to a predetermined operative position, and manually operable means by which the operator may shift the edge-guide at will to another predetermined operative position. Preferably, and as herein illustrated, one treadle may be utilized to shift the edge-guide, and another treadle is utilized to retract the presser-foot and to control the clutch, to the end that both hands of the operator may be used to shift and control the work in consonance with the results produced with the treadles.

Some styles pertaining to the eyeletting of shoe-uppers call for a "one-eyelet spread" and others call for a "two-eyelet spread." In the first of these only the eyelet nearest the throat is set back a greater distance from the lacing-edge of a quarter than the other eyelets in that quarter. In a two-eyelet spread the first and second eyelets from the throat are both set back farther than the others, and the first is set back farther than the second. This latter arrangement involves an additional problem for which the present invention provides a solution which, as herein set forth, is embodied in an improved combination that includes, among other elements, manually controllable means arranged to lock the edge-guide at an intermediate operative position. This locking device is so combined with the other elements of the combination that its use is optional, to the end that it may be rendered effective under conditions that call for a two-eyelet spread but ineffective under conditions that call for a one-eyelet spread.

With regard to that aspect of the invention that deals with a two-eyelet spread, an improved feature consists in a novel combination comprising power-operated mechanisms arranged to insert fasteners successively in a series and to feed the work to space the fasteners one from another, a

clutch by which said mechanisms are operated, a clutch-controlling member, a movable edge-guide, and means controlled by said clutch-controlling member for locking and releasing the edge-guide.

5 The features above referred to and other novel features of the invention are hereinafter described and illustrated in the accompanying drawings which disclose two embodiments of the invention.

10 Referring to the drawings,

Fig. 1 is a front elevation of an eyeletting machine equipped with mechanism embodying the present invention;

15 Fig. 2 is a perspective view of various controls with which the machine is provided, the controls being pictured approximately in the relative positions that they occupy in the operative assemblage;

20 Fig. 3 is a top plan view, partly in section, including the work-supporting table, the presser-foot, the movable edge-guide and some of the parts included in the train of mechanism for shifting the edge-guide;

25 Fig. 4 is a top plan view, partly in section, of certain parts pictured in Fig. 3 (see line IV—IV of Fig. 5);

Fig. 5 is a front elevation, partly in section, of the assemblage represented in Fig. 4;

30 Fig. 6 is a front view of a shoe upper distorted to present the fronts of the two quarters in a substantially flat plane confronting the observer. This view represents a typical example of eyeletting work for which the present invention is provided;

35 Fig. 7 is a view similar to Fig. 3 but showing a modification of the edge-guide and the controls therefor, and

Fig. 8 is a sectional view of the structure intersected by line VIII—VIII of Fig. 7.

40 The general organization of the eyeletting machine herein illustrated is similar to that more fully shown and described in the aforesaid Letters Patent No. 1,228,768 and for this reason the following description thereof is purposely abbreviated consistently with its purpose of providing a suitable groundwork for a subsequent description of the novel features of construction that embody the essence of the present invention.

45 An article of work to be eyeleted, for example, a shoe-upper, is laid upon a fixed work-supporting table 15 against which it is clamped and periodically released by a presser-foot 16. The eyelets are inserted upwardly by power-operated mechanism including a tool 17 to which they are delivered by a movable raceway 18. The tool 17 is carried by a vertically movable plunger 19 that receives its operating motions from a rotary cam shaft (not shown). The plunger 19 is arranged in fixed bearings in the frame 10. Eyelet-receiving holes are punched successively in the work-piece and the work is fed step by step from right to left by a combined punching and clenching tool 20 that operates downwardly against the work. This tool is carried at the lower end of a plunger 21 arranged to be reciprocated up and down in bearings formed in a horizontally movable feed-carriage 22. For present purposes it is not necessary to show or describe the details of construction of the power-operated mechanism for reciprocating the feed-carriage, but it is to be understood that, when the parts occupy their initial positions, (Fig. 1), the feed-carriage stands at the right-hand limit of its path of feeding movement and that the tool 20 is then out of alignment with the eyelet-inserting tool 17.

Moreover, the tool 20 is initially raised and the tool 17 is initially depressed. The fastener-inserting mechanism and the work-feeding mechanism both derive their operating motions from a stopping and starting mechanism under the control of the operator and designed to stop the machine in every case when the parts are in the positions represented in Fig. 1.

5 When the machine is set in operation, the upper plunger 21 descends to cause the punching portion of the tool 20 to punch or cut an eyelet-receiving hole in the work-piece lying on the table 15. The hole having been punched, the pressure of the tool against the work-table is relieved but the punch remains in the hole that has just been punched thereby while the feed-carriage 22 moves to feed the work one step from right to left and to locate the tool 20 in register with the eyelet-inserting tool 17. In the meantime, the latter rises, slowly at first, to insert its central spindle 20 through an eyelet at the delivery end of the raceway 18, whereupon the latter is automatically retracted from the path of that tool. The tool 17 continues to rise far enough to insert the barrel of the eyelet through the eyelet-receiving hole in 25 the work and to clench the upper end of the eyelet-barrel against the tool 20. At this point in the cycle, the lower tool 17 descends and the upper tool 20 rises and moves from left to right, both tools being thus returned to their initial 30 positions.

35 The presser-foot 16 is normally maintained in its work-clamping position by the force of a spring but it is automatically lifted to release the work only during that portion of the cycle in which the work-feeding mechanism operates. In addition, the machine is provided with treadle-mechanism by which the presser-foot may be manually lifted to facilitate insertion and removal of the work. As shown in Figs. 2 and 3, the presser-foot 40 is affixed to the upper end of a vertical rod 23 arranged to slide in bearings formed in the main frame 10 of the machine. The work-clamping effect of the presser-foot is derived from a compression spring 24, the upper end of which is seated against a boss on the frame and the lower end of which is seated on a collar 25 clamped on the rod 23. The automatic mechanism for lifting the presser-foot derives its motion as heretofore from the cam-shaft, and the manually operative mechanism for lifting the presser-foot includes a lifting lever 26 connected to the frame 10 by a horizontal fulcrum-stud 27. One arm of the lever 26 underlies the lower end of the rod 23 and is not affected by automatic operation of the 45 rod. The other arm of the lever 26 is operatively connected with the heel-end of a treadle 28 by any suitable operating connection, such as a chain 29. This treadle is preferably arranged to be operated by the operator's right foot. The arrangement of the parts is such that downward motion of the heel-end of the treadle will raise the presser-foot. In practice this motion is brought into use only when the automatic mechanisms of the machine are at rest.

50 The treadle 28 is mounted on a floor-stand or bracket 30 to which it is connected by a fulcrum-pin or trunnions 31 located approximately midway between the toe and heel of the treadle.

55 In accordance with former practice, this treadle is used also to control a clutch by which the fastener-inserting mechanism, the work-feeding mechanism, and other automatic mechanisms of the organization are driven. For this purpose, the toe of the treadle 28 is provided with a lat- 60

erally extending boss 32 to receive a hook 33 at the lower end of a treadle-rod 34 comprising two sections adjustably connected by a coupling 35. The upper end of the upper section of this rod 5 extends through an eye in the lower end of a vertical clutch-controlling rod 36 arranged to slide in bearings formed in the frame 10 of the machine. The rod 36 is surrounded and normally raised by a helical compression spring 37 seated 10 on a portion of the frame 10 and acting against a collar 38 secured to the rod. Thus, when the toe-end of the treadle 28 is depressed, it will depress the clutch-controlling rod 36 against the spring 37 without affecting the presser-foot lifter 15 26. On the other hand, when the heel-end of this treadle is depressed to lift the presser-foot, the boss 32 at the toe-end of the treadle will merely rise relatively to the hook 33 without imparting any upward movement to the treadle-rod 34.

Any suitable or preferred type of clutch may be provided for driving the automatic mechanisms of the organization consistently with the requirements herein set forth. The clutch illustrated in the accompanying drawings embodies a well-known construction which is partially illustrated in the aforesaid Patent No. 1,228,768 but more fully shown and described in United States Letters Patent No. 1,534,107, granted April 21, 1925 on application of P. R. Glass. It may be ascertained by reference to the patent last-mentioned that the clutch is set in operation by drawing down the controlling rod 36 and that the clutch will continue to drive the shaft on which it is mounted so long as the controlling rod is depressed but, when the latter is released, it will not only disengage the clutch but will also arrest the shaft at a predetermined point in its cycle, to the end that the automatic mechanisms will all come to rest in certain positions consistent with their functions. In a clutch of this type, the driving member is a continuously rotating pulley 39 loosely mounted on the cam-shaft and provided with a groove to receive a 40 driving belt (not shown).

Although the work-feeding mechanism in a machine of this type is well known and is more fully illustrated and described in the aforesaid Letters Patent No. 1,228,768, it is desirable to 50 point out for a purpose hereinafter explained that it is capable of being regulated to vary the length of the steps of work-feeding movement, to the end that the spacing of the eyelets one from another may be varied accordingly. It will not be necessary to the pointing out of this purpose to include herein a complete description of all the elements comprised in the work-feeding mechanism but it will be sufficient to explain that the length of the feeding steps may be altered by moving a regulator 40 (Fig. 3) to various positions. This regulator is provided with a stem 41 arranged to turn in a bearing provided by a boss 42 projecting from the frame 10. One arm of this regulator overlies a stationary plate 60 43 of segmental form affixed to the frame and provided with numerous holes 44 adapted to receive pins 45 whereby the regulator may be maintained in any desired position of adjustment. Moreover, a tension spring 58 is connected to this 65 regulator and tends normally to turn it in the direction indicated by an arrow in Fig. 3. Thus, the regulator may be held against a pin 45 inserted in any one of the holes 44 but the regulator may, nevertheless, be moved in opposition to the 70 spring, provided such movement is not obstructed.

ed by a pin in one of the other holes. This combination provides for manually moving the regulator counter to the arrow whenever it is desired, for example, to increase temporarily the length of the feeding steps.

For the purpose last mentioned, the illustrated machine is provided with a train of mechanism arranged to be operated by a treadle other than the clutch-controlling treadle 28. Moreover, the regulator 40 is provided with an arm 46 having an 10 eye 47 in its outer end. Referring now to Fig. 2, the train of mechanism about to be described comprises a treadle 48 arranged to be operated by the operator's left foot, a treadle-rod 49 in two sections adjustably connected by a coupling 50, a bell-crank lever 51 and a connecting rod 52 extending from the bell-crank lever toward the regulator 40 and provided with a hook 53 adapted to be inserted into the eye 47. As shown in 15 Fig. 2, this treadle mechanism occupies its normal position, the toe portion of the treadle being raised. Now, if the hook 53 of the connecting rod 52 be operatively connected to the regulator 40, downward movement of the toe portion of the treadle 48 will swing the regulator counter to the 20 arrow in Fig. 3 and thus increase the length of the feeding steps imparted to the work, but, when the treadle is released, the regulator will be returned by its spring to its former position 25 against the pin 45.

It is now to be understood that the several mechanisms hereinbefore described are all well known and are entirely adequate for eyeletting shoe-uppers in the conventional manner, that is, by locating all the eyelets of a series at a uniform 30 distance from the lacing-edge by which the upper is guided while in process of being eyeletted. On the other hand, no satisfactory means for machines of this type has heretofore been provided to locate the eyelets symmetrically according to 35 the arrangement exemplified in Fig. 6. Nevertheless, some operators use a templet and a prick-punch to mark the points at which the eyelets are to be inserted and then locate the upper manually in the desired position for each eyelet individually, thus sacrificing the eyelet-spacing effect of the work-feeding mechanism, speed of production and, to some extent, accuracy. Moreover, the use of templets imposes restrictions not only 40 with regard to the spacing of the eyelets one from another but also with regard to their proximity to the lacing-edges of the uppers.

As shown in Fig. 6, the upper 55 is provided with visible eyelets of conventional type indicated by the numerals 1, 2, 3, 4, 5, and 6, the order of 45 ascendency in one of the quarters being from the throat 56 toward the top and that in the other quarter being from the top toward the throat to indicate the order in which the eyelets are inserted, as more fully explained hereinafter. The 50 lacing-edges of the quarters are indicated at 57. It is to be observed that the four eyelets in each quarter, counting from the top, are uniformly 55 distant from the lacing-edges, that the eyelets 1 and 6 nearest the throat are set back a relatively great distance from the lacing-edges, and that the second eyelets 2 and 5 from the throat are set back an intermediate distance from the lacing-edges. This arrangement of eyelets is commonly termed a two-eyelet spread because the 60 two lowest eyelets of each series are set back more than the eyelets above them. In some cases, however, only the lowest eyelet of each series is set back to provide what is commonly termed a 65 one-eyelet spread. The spread arrangement, 70

whether of one-eyelet spread or two-eyelet spread, constitutes the problem toward which the present invention is directed and by which the desired results, with provisions for various degrees of spread, may be obtained with the novel mechanisms hereinafter described. The drawings include two modifications of apparatus by which the quarters of an upper may be guided and controlled to insure symmetry in such eyeletting.

As shown in Fig. 3, an edge-guide 60 is mounted on the work-supporting table 15 and connected to the under side thereof by a fulcrum-stud 61 which provides for shifting the work-engaging portion of the guide toward the front and rear of the machine, that is, in directions transverse to the normal path of travel in which the work is fed by the feeding mechanism hereinbefore described. In Fig. 3, the edge-guide is represented in solid lines as retracted to its rear limit of shifting movement to provide for a relatively great distance between the lacing-edge 57 of a right quarter and the point at which the first eyelet is to be inserted nearest the throat of that quarter. Dotted lines represent the work-engaging portion of the edge-guide in its forward position where it will stand for the eyelets to be inserted nearest the lacing-edge 57 of the quarter. It is to be understood, moreover, that the work-engaging portion of the guide may also be locked at an intermediate operative position for the second eyelet from the throat of a quarter when a two-eyelet spread is desired.

Describing first the modification illustrated in Figs. 1 to 5, inclusive, the edge-guide 60 is provided with an integral arm or extension 62, the outer end of which is normally drawn to the rear by a tension-spring 63. A link 64 connects the arm 62 with a bell-crank lever 65 mounted on a stationary fulcrum-stud 66. An arm 67 of this bell-crank lever lies adjacent to the arm 46 of the feed regulator but at a slightly lower level to provide clearance for unobstructed movement of the arms. An eye 68 in the arm 67 is adapted to receive the hook 53 of the connecting rod 52, the connecting rod being so connected with the lever 51 as to permit the hook 53 to be transferred from the eye 47 to the eye 68 whenever it is desired to use the treadle 48 (Fig. 2) for the purpose of retracting the edge-guide. It may now be understood that when the connecting rod 52 is operatively connected to the arm 67, depression of the toe-portion of the treadle 48 will shift the work-engaging portion of the edge-guide 60 toward the rear, and that the spring 63 will normally shift the edge-guide toward the front when this train of mechanism is released. Moreover, the edge-guide may be arrested and locked at its intermediate operative position irrespective of its direction of shifting movement.

For the latter purpose, the bell-crank lever 65 is provided with a locking arm 69 (Figs. 4 and 5) in which a hole 70 is formed to receive a manually controlled locking-pin 71. This pin is arranged 65 in a socket 72 carried by an adjustable plate 73 mounted upon and supported by a fixed plate 74 rigidly secured to the plate 43 by an attaching screw 75 and a spacing sleeve 76. The stud 66 extends through both plates and permits angular 70 adjustment of the plate 73 to locate the locking-pin 71 at the desired position. A device for adjusting the plate 73 comprises a stud 77 arranged to turn in a bearing in the fixed plate 74 and provided with a handle 78 by which it may be turned. An eccentric portion 79 of this stud oc-

cupies a notch in the adjustable plate 73 and is thus rendered effective to change the location of the locking-pin 71 within suitable limits. The adjusting stud 77 is provided with a head 80 and a compression spring 81 by which the head is clamped against the plate 73 and by which the latter is clamped against the fixed plate 74 with pressure sufficient to prevent lateral displacement of the locking-pin otherwise than by operating the handle 78.

The locking arm 69 is spaced from the adjustable plate 73 slightly to provide for the reception of a thin guard-plate 82, the purpose of which is to prevent the locking-pin 71 from engaging the locking arm 69 under conditions that do not require locking the edge-guide 60 in an intermediate position as, for example, when eyeletting shoe uppers with a one-eyelet spread. This guard plate is provided with a keyhole slot 83, the larger portion of which is of a size that will permit the locking-pin 71 to pass through it and enter the hole 70 in the locking arm. The narrower portion of the keyhole slot is occupied by a small vertical guide-pin 84 driven into the adjustable plate 73. This pin also serves as a stop to locate the larger portion of the keyhole slot in register with the locking pin. The guard-plate projects beyond the outer end of the adjustable plate 73 and is bent downwardly to provide a tongue or flange by which it may be operated manually. This flange is provided with a small hole or a notch to receive a horizontal guide-pin 85 driven into the plate 73.

The locking-pin 71 is normally projected upwardly by a compression spring 86 contained in the socket 72. The shank of the locking-pin projects below the bottom of the socket and is provided with a loop 87 of wire that limits its upward movement and also provides for connection with some suitable means for retracting the pin to release the locking arm and the edge-guide. Fig. 2 illustrates one form of means suitable for this purpose which comprises a rod or wire 88 the upper end of which is screwed into a hook 54 and the lower end of which is bent to form an elongated eye or loop 89 through which one arm of the presser-foot-lifter 26 may extend. The elongation of the loop 89 provides for lost motion whereby the presser-foot-lifter may, under certain conditions, partially lift the presser-foot to release the work without taking control of the locking pin 71. The screw-connection between the rod 88 and the hook 54 provides for regulating the extent of the lost motion afforded by the loop 89.

Operation

Assuming that it is desired to use the described machine for eyeletting a shoe-upper with a two-eyelet spread according to the arrangement exemplified in Fig. 6, the operator will first depress the heel-portion of the treadle 28 far enough to release the edge-guide 60. Now, if the operator first selects the right-hand quarter for operation, he will shift the edge-guide to the rear as far as it will go by depressing the toe-portion of the treadle 48 with the left foot, meanwhile maintaining the presser-foot lifted by depression of the heel-portion of the treadle 28. Having thus located the edge-guide in the position represented by solid lines in Fig. 3, and having placed the lacing-edge 57 of the right-hand quarter against it as also represented in that figure, with due regard to the distance between the throat of the quarter and the point at which

the first eyelet-receiving hole will be punched, the next controlling movement is to depress the toe of the right foot on the treadle 28 while continuing to hold down the treadle 48 with the toe of the left foot. The toe of the right foot will draw down the clutch-controlling rod 36 to trip the clutch by which the machine is set in operation, but this depression of the controlling rod will continue only long enough to cause one cycle of rotation of the clutch. The machine will thus be caused to insert the first eyelet of the series nearest the throat of the quarter but at the greatest distance from the lacing edge 57 and incidentally will feed the quarter one step before coming to a stop. Now, the heel of the right foot will be depressed for enough to raise the presser-foot but not so far as to take control of the locking-pin 71. The operator will now release the treadle 48 with the left foot and the spring 63 will shift the edge-guide 60 toward the front and with it the piece of work upon which the operator's hands will rest lightly to guard against its displacement to the right or left but still with sufficient pressure to maintain the lacing-edge 57 against the edge-guide. When this shifting of the edge-guide toward the front has brought the hole 70 of the locking arm into register with the locking-pin 71, the latter will be projected into the hole by its spring 86 and the edge-guide will thus be arrested and locked in its intermediate operative position. Now, the operator will again trip the clutch by depressing the toe-portion of the treadle 28 with the right foot only long enough to cause one more cycle of rotation of the driving clutch. Incidentally, the presser-foot will be restored once more to its automatic control and operation. Thus, the second eyelet of the series will be inserted at an intermediate distance from the lacing-edge 57 of the quarter and the machine will feed the work one more step before stopping. Again the operator will depress the heel of the right foot on the treadle 28, but this time the depression will be sufficient not only to lift the presser-foot but also to withdraw the locking-pin 71 from the hole in the locking arm 69. The edge-guide 60 will now be moved to its extreme forward position by the spring 63, and the presser-foot will be restored to its automatic control and operation by rocking the treadle 28 with the toe of the right foot. At this point, the shoe-quarter is in readiness to receive the third eyelet, which will be the first of four eyelets all to be located at the minimum distance from the lacing-edge 57. Consequently, the toe portion of the treadle 28 will be depressed long enough to cause four cycles of rotation of the clutch before the next stop. At the completion of this series of eyelets, but the heel of the operator's right foot will rock the treadle 28 to lift the presser-foot so that the finished quarter may be removed from the work-table 15 and the left-hand quarter may be placed thereon.

When the left-hand quarter is presented for operation, its top edge will be at the left and its throat at the right, and the first four eyelets will be inserted without interruption and at points uniformly near its lacing-edge 57. The operator will therefore operate the treadle 28 to stop the machine between the fourth and fifth eyelets and will cause the treadle 28 to raise the presser-foot when this point in the series has been reached. Now, with the toe of the left foot the operator will depress the treadle 48 to shift the edge-guide 60 to the rear, meanwhile sliding the

quarter to the rear with his hands to maintain the lacing-edge 57 against the edge-guide. Again, the locking-pin 71 will arrest the edge-guide and lock it in its intermediate operative position to determine the location of the fifth eyelet of the series. Now, with the toe of the right foot the operator will operate the treadle 28 to cause only one cycle of rotation of the driving clutch, after which the heel of the right foot and the toe of the left foot will both be depressed, one to lift the presser-foot and to release the edge-guide and the other to retract the edge-guide to its extreme rear position. Again, while retracting the edge-guide, the operator will shift the quarter to the rear and thus maintain its lacing-edge 57 against the edge-guide. Now, still bearing down on the treadle 48 with the left foot to maintain the edge-guide in its extreme rear position, the operator will once more depress the toe-portion of the treadle 28 for the sixth eyelet of the series. 10 15 20

It may be readily understood that although the described mechanism provides for three predetermined operative positions of the edge-guide 60, the operator may, at will, utilize any one of them at any time. If the guard-plate 82 (Fig. 5) is pushed in to prevent operation of the locking-pin it will facilitate manipulating the controls in accordance with the requirements of a one-eyelet spread. Moreover, if desired, the edge-guide may be left in its forward position if it is desired to insert all the eyelets at a uniform distance from the lacing-edge or other guiding-edge of a work-piece. 25 30

It has already been explained how the handle 18 may be utilized to regulate the intermediate operative position of the edge-guide. In addition, the illustrated construction includes means for regulating the two extreme operating positions. For the latter purpose, the arm 62 of the edge-guide (Fig. 3) is provided with a segmental series of teeth 90 in the form of an incomplete screw-thread, and they are arranged to cooperate with a screw-thread 91 formed on an axially movable and rotatable stud 92. This stud 92 is arranged to slide and turn in two smooth cylindric bearings formed in ears 93 on the under side of the work-supporting table 15. A knob 94 on one end of the stud and an adjustable nut 95 screwed on the other end are arranged to limit the extent of axial movement of the stud by engaging the ears 93. The extent of this movement may be varied by adjusting the nut 95, and the relation of the edge-guide to the stud may be changed by turning the latter. These two adjustments in conjunction with that provided by the adjusting device 18 (Figs. 4 and 5) provide for establishing and varying the three operative positions of the edge-guide. 40 45 50 55 60

The modification illustrated in Figs. 7 and 8 embodies the same principles as the construction heretofore described and is adapted to be operated and controlled in the same manner by the treadle mechanisms illustrated in Fig. 2. In both constructions the work-supporting table is detachably secured to the frame 10 by a bolt 11 (Fig. 1) and dowels (not shown). The connecting rod 52' (Fig. 7) is arranged to communicate motion from the bell-crank lever 51 to a bell-crank lever 65' mounted on a supporting bracket 74' to which it is connected by a fulcrum pin 66'. A link 63' is arranged to communicate motion from the bell-crank 65' to the edge-guide 60', the arrangement of the connections being such that the edge-guide is normally moved to its forward position by a 70 75

tension-spring 63' attached to the treadle-rod 49 (Fig. 2). In this device the pin 71' for locking the edge-guide in an intermediate operative position is arranged to enter a hole 70' in the arm 62' of the edge-guide. A suitable operating connection for retracting the locking-pin may be provided by a rod or wire 88' having a hook at each end, that at the upper end being connected with the locking-pin and that at the lower end being inserted through one of the links of the chain 29 running to the presser-foot lifter. The locking-pin is normally raised by a compression spring 86'. Both the locking-pin and the spring are arranged in a socket 72' formed on a segmental plate 73'. This plate is adjustably mounted in segmental grooves formed in an extension 15' of the work-supporting table. The curvatures of the plate 73' and the grooves in which it is mounted are concentric with respect to the fulcrum stud 61 of the edge-guide. An eye-bolt 79' surrounding the socket 72' extends through an adjusting nut 78' to provide for shifting the locking-pin laterally and maintaining it at any desired operative position. The nut 78' is mortised into an ear 96 formed on the extension 15' and may turn relatively thereto but may not move axially. The eye-bolt and the adjusting nut are maintained in cooperative relation to the ear 96 by a collar 97 secured to the socket. The lower end of the locking-pin projects below the socket and is provided with a screw-thread whereby a coupling eye 98 may be attached to form connection with the operating rod 88'. A nut 99 is also carried by the locking-pin to limit upward movement thereof.

As in the locking device first described, depression of the heel-portion of the treadle 23 will first lift the presser-foot to release the work, and if continued thereafter will depress the locking-pin 71' to release the edge-guide so that both the work and the edge-guide may be shifted together without obstruction.

The device shown in Figs. 7 and 8 is further provided with a spring-pressed detent 100 which is effective to maintain the edge-guide in its extreme forward position. Consequently, if desired, the treadle 48 for the left foot, and all the operating connections for communicating motion therefrom to the edge-guide, may be omitted without depriving the latter of any necessary control. For example, some operators may prefer to shift the edge-guide by hand from one operative position to another, as by grasping the outer end of the arm 62'. Under these circumstances, the locking-pin 71' and the nut 95 will still function as hereinbefore explained to arrest the edge-guide at its two other operative positions. The detent 100 is a vertically movable pin arranged in a socket 101 formed on the work table and is normally pressed upwardly by a compression spring (not shown) contained in the socket. The upper end of the detent is V-shaped (see Fig. 8) and is adapted to enter a V-shaped groove 102 in the adjusting stud 92' which, in all other respects, embodies the same construction and operates in the same manner as the corresponding stud 92 shown in Fig. 3. Although the detent 100 will yield to the camming effect of the stud 92' its retaining power is sufficient to withstand any usual pressure of the work against the edge-guide.

Having described my invention, what I claim as new and desire to secure by Letters Patent of the United States is:

1. A fastener-inserting machine comprising a work-support, a presser-foot, manually operable means arranged to retract said presser-foot, pow-

er-operated mechanisms arranged to insert fasteners successively in a series and to feed the work to space the fasteners one from another, a clutch controlled by said manually operable means to operate said mechanisms, a movable edge-guide, a spring arranged to move said edge-guide to a predetermined operative position, and manually operable means by which the operator may shift said edge-guide at will to another predetermined operative position. 10

2. A fastener-inserting machine comprising power-operated mechanisms arranged to insert fasteners successively in a series and to feed the work to space the fasteners one from another, a clutch by which said mechanisms are operated, 15 a clutch-controlling member, a movable edge-guide, and means controlled by said clutch-controlling member for locking and releasing said edge-guide.

3. A fastener-inserting machine comprising 20 mechanism arranged to insert fasteners successively in a series, mechanism arranged to feed the work to space successive fasteners one from another, a driving clutch by which said mechanisms are operated, a clutch-controlling member, 25 an edge-guide movable to and fro transversely of the path of the work, a spring-pressed member arranged normally to lock said edge-guide, and means operable by said controlling member for moving said spring-pressed member to release said edge-guide. 30

4. A fastener-inserting machine comprising mechanism arranged to insert fasteners successively in a series, mechanism arranged to feed the work to space successive fasteners one from 35 another, a driving clutch by which said mechanisms are operated, a clutch-controlling member, an edge-guide movable to and fro transversely of the path of the work, spring-pressed means arranged to arrest said edge-guide positively at an intermediate point in its range of to-and-fro movement, and means operable by said controlling member for retracting said spring-pressed means from its arresting position. 40

5. A fastener-inserting machine comprising 45 mechanism arranged to insert fasteners successively in a series, mechanism arranged to feed the work to space successive fasteners one from another, a driving clutch by which said mechanisms are operated, a clutch-controlling member, an edge-guide movable to and fro transversely of the path of the work, a spring-pressed member arranged to lock said edge-guide in one of its operative positions, adjusting means for varying the location of said spring-pressed member, and 50 means operable by said controlling member for moving said spring-pressed member to release said edge-guide. 55

6. A fastener-inserting machine comprising mechanism arranged to insert fasteners successively in a series, mechanism arranged to feed the work to space the fasteners one from another, a driving clutch by which said mechanisms are operated, a clutch-controlling member, an edge-guide movable to and fro transversely of 60 the path of the work, a spring arranged to shift said edge-guide in one direction, a treadle arranged to retract said edge-guide in the opposite direction, and means arranged to lock said edge-guide in an intermediate position, said locking 65 means being controllable by said clutch-controlling member to release the edge-guide. 70

7. A fastener-inserting machine comprising a work-supporting table, a presser-foot arranged to clamp the work thereon, power-operated 75

- mechanisms arranged one to insert a series of fasteners successively and the other to feed the work to space the fasteners one from another, an edge-guide movable to and fro, a spring-pressed member arranged normally to lock said edge-guide, and a manually operable controller arranged to retract said presser-foot and said spring-pressed member with one motion to release the work and said edge-guide.

10. A fastener-inserting machine comprising a work-supporting table, a presser-foot arranged to clamp the work thereon, power-operated mechanisms arranged one to insert a series of fasteners successively and the other to feed the work to space the fasteners one from another, an edge-guide movable to and fro, a spring-pressed member arranged normally to lock said edge-guide, a manually operable controller arranged to retract said presser-foot and said spring-pressed member with one motion to release the work and said edge-guide, and means under control of said controller for starting and stopping said power-operated mechanisms.

15. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, spring-pressed means arranged normally to lock said edge-guide, and a controller movable in one direction to retract said presser-foot and said spring-pressed means.

20. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide in an intermediate operative position, and a controller movable in one direction to retract said presser-foot and said spring-pressed arresting member.

25. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

30. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

35. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

40. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

45. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

50. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

55. A fastener-inserting machine comprising a work-supporting table, a presser-foot arranged to clamp the work thereon, mechanism arranged to insert fasteners successively in a series, mechanism arranged to feed the work to space the fasteners one from another, a driving clutch by which said mechanisms are operated, an edge-guide movable to and fro transversely of the path of the work, a spring-pressed member arranged normally to arrest said edge-guide at an intermediate point in its range of to-and-fro movement, and a controller movable in one direction to retract said presser-foot and said arresting member.

60. A fastener-inserting machine comprising a work-supporting table, a presser-foot arranged to clamp the work thereon, power-operated mechanisms arranged one to insert a series of fasteners successively and the other to feed the work to space the fasteners one from another, two treadles one of which is operative to retract said presser-foot, an edge-guide connected to the other one of said treadles to be shifted thereby to various operative positions, and a spring-pressed member arranged normally to lock said edge-guide but operable by one of said treadles to release the edge-guide.

65. A fastener-inserting machine comprising a work-supporting table, a presser-foot arranged to clamp the work thereon, power-operated mechanisms arranged one to insert a series of fasteners successively and the other to feed the work to space the fasteners one from another, a driving clutch by which said power-operated mechanisms are operated, a treadle by which said clutch is controlled, a movable edge-guide, a treadle by which said edge-guide may be shifted to various operative positions, a spring-pressed member arranged normally to lock said edge-guide but controllable by said clutch-treadle to release the edge-guide, and means operable by one of said treadles to retract said presser-foot.

70. A fastener-inserting machine comprising a work-supporting table, a presser-foot arranged to clamp the work thereon, power-operated mechanisms arranged one to insert a series of fasteners successively and the other to feed the work to space the fasteners one from another, a driving clutch by which said power-operated mechanisms are operated, a movable edge-guide, two treadles one of which controls said clutch and the other of which is arranged to shift said edge-guide to various operative positions, means controllable by one of said treadles to secure and release said edge-guide, and means operable by one of said treadles to retract said presser-foot.

75. A fastener-inserting machine comprising a work-supporting table, a presser-foot arranged to clamp the work thereon, power-operated mechanisms arranged one to insert a series of fasteners successively and the other to feed the work to space the fasteners one from another, a movable edge-guide, spring-pressed means arranged normally to lock said edge-guide, two treadles one of which is arranged to control said spring-pressed means and the other to shift said edge-guide, and means by or through which the treadle first specified is effective to retract said presser-foot.

80. A fastener-inserting machine comprising power-operated mechanisms for inserting fasteners successively in a series and for feeding the work to space the fasteners one from another, a movable edge-guide, a controlling member movable therewith, a spring-pressed locking member arranged to cooperate with said controlling member, and manually operable means arranged to arrest said power-operated mechanisms and retract said locking member to release said controlling member.

85. A fastener-inserting machine comprising power-operated mechanisms for inserting fasteners successively in a series and for feeding the work to space the fasteners one from another, a movable edge-guide, a controlling member movable therewith, a spring-pressed locking member arranged to cooperate with said controlling member, adjustable means by which said locking member is mounted and by which it may be shifted laterally to various operative positions within the range of movement of said controlling member, and manually operable means by which said locking member may be retracted to release said controlling member.

90. A device for variably controlling the guidance of work in a fastener-inserting machine of the type in which the fasteners are inserted successively in a series as the work is fed automatically to space them one from another, said device comprising a detachable work-supporting table along which the work may be fed as aforesaid.

- an edge-guide mounted on said table and movable to various operative positions, yieldable means arranged normally to maintain said edge-guide in one of its operative positions, and a 5 spring-pressed member arranged to lock said edge-guide in another one of its operative positions, said spring-pressed locking member being retractable to release the edge-guide.
19. A fastener-inserting machine comprising 10 power-operated mechanism for inserting fasteners successively in a series, regulatable work-feeding mechanism by which the work is fed with steps of variable length to space the fasteners one from another, starting and stopping means 15 by which said mechanisms are operated, movable work-guiding means, and a treadle-operated mechanism a movable element of which is formed and arranged to be operatively engaged alternatively 20 with said work-guiding means on the

one hand and with a regulating element of said work-feeding mechanism on the other hand.

20. A fastener-inserting machine comprising power-operated mechanism for inserting fasteners successively in a series, regulatable work-feeding mechanism by which the work is fed with steps of variable length to space the fasteners one from another, starting and stopping means by which said mechanisms are operated, 10 movable work-guiding means a member of which is located adjacent to a regulating member of said work-feeding mechanism, and a treadle-operated mechanism including a connecting-rod arranged to be operatively engaged alternatively with said members, the connecting-rod and said 15 members having cooperative hook-and-eye formations to facilitate transferring the operating connection from one of said members to the other and vice versa.
